CONVERTIBLE TOY CAP GUN

John W. Ryan, 688 Nimes Road, Bel Aire, Calif.

Filed Apr. 16, 1965, Ser. No. 84,833

Term of patent 14 years

(Cl. D34—15)

FIGURE 1 is a side elevational view of a convertible toy cap gun, showing my new design,

FIGURE 2 is an end elevational view, taken from the right, of the structure shown in FIGURE 1,

FIGURE 3 is a side elevational view of the side opposite that seen in FIGURE 1,

FIGURE 4 is an end elevational view taken from the right as seen in FIGURE 3,

FIGURE 5 is a top plan view of the structure shown in FIGURES 1 to 4,

FIGURE 6 is a front elevational view of the gun in a closed position when converted to a toy camera,

FIGURE 7 is a rear elevational view of FIGURE 6,

FIGURE 8 is an end elevational view taken from the right of FIGURE 6,

FIGURE 9 is an end elevational view taken from the right of FIGURE 7, and

FIGURE 10 is a top plan view of the arrangement as shown in FIGURES 6 through 9.

I claim:

The ornamental design for a convertible toy cap gun, as shown and described.
